CLAIM

The ornamental design for that represents luminaire, as shown and described.

DESCRIPTION

- 1.1 is a front view.
1.2 is a rear view.
1.3 is a top view.
1.4 is a right side view.
1.5 is a left side view.
1.6 is a bottom view.
1.7 is a perspective view.

(Continued)

The broken lines in the drawings illustrate portions of luminaire and form no part of the claimed design.
